UNITED STATES PATENT OFFICE.

ALBERT F. FIFIELD, OF NEWARK, NEW JERSEY, ASSIGNOR TO THE SINGER MANUFACTURING COMPANY, A CORPORATION OF NEW JERSEY.

BUTTON-SEWING MACHINE.

1,373,227.

Specification of Letters Patent. Patented Mar. 29, 1921.

Application filed January 15, 1917. Serial No. 142,413.

To all whom it may concern:

Be it known that I, ALBERT F. FIFIELD, a citizen of the United States, residing at Newark, in the county of Essex and State of New Jersey, have invented certain new and useful Improvements in Button-Sewing Machines, of which the following is a specification, reference being had therein to the accompanying drawings.

10 My invention relates broadly to a sewing machine having a stop mechanism for arresting its operation after a predetermined number of stitches have been made. Machines of this type are usually employed for 15 buttonholing or barring or for sewing articles such as buttons to a garment and the configuration of the stitches is predetermined by a work-clamping mechanism having suitable jogging or traveling movements imparted thereto from a controller cam.

20

An object of my invention is to equip machines of this type with implements insuring the formation of stitches, insuring 25 their formation as tight at the beginning as at the end of a cycle of operations, and insuring the severance of the thread-ends close to the under side of the body-fabric, thereby increasing the durability as well as enhancing the appearance of the finished 30 product.

It is concerned with a machine for performing these functions which will be simple but reliable in action; reliable in 35 severing the thread and reliable in holding the severed end of the thread so that subsequently formed stitches will be tight. It is further concerned with the amount of thread used and aims to consume as little 40 as possible while attaining certainty of operation.

In its preferred construction the machine is provided beneath the throat-plate with a detainer, a nipper, movable shear and co- 45 operating ledger-blades, operating upon the beginning end of the thread, and a cutter for severing the finishing end of the thread from the supply. A bellcrank pivoted to the throat-plate carries in superimposed re- 50 lations the nipper and movable shear-blade, the former being arranged between the latter and the throat-plate against which it grips the thread. The cutting edge of the movable shear-blade, is slightly to the

rear of the edge of the nipper. The bell- 55 crank is actuated from a slide-rod extending parallel with the looper-shaft below the bed-plate of the machine and actuated by a lever pivoted above the bed-plate adjacent the controller-cam from peripheral 60 projections on which the said nipper, detainer and movable shear-blade are advanced in a two-stage movement at the beginning of the sewing operation and the nipper and movable shear-blade are retract- 65 ed after a few stitches have been made. The first stage of the above mentioned movement engages a thread-detainer loosely with the thread end which has been pulled through the work by the looper during the first re- 70 ciprocation of the needle and deflects it to one side across the cutting edge of a ledger-blade fixed to the throat-plate and underlying both the nipper and movable shear-blade which have been advanced at the same time, 75 the nipper having a notch for positioning the needle-thread preliminary to its being gripped. The second stage of movement further advances the nipper, detainer, and knife simultaneously to effect a gripping of 80 the beginning end of the thread against the throat-plate followed immediately by a severance and seizure of the extreme end of the thread by the movable shear-blade and detainer respectively, the latter gripping the 85 waste end of thread against the fixed shear-blade. After enough stitches have been made to anchor the beginning end of the thread the nipper and movable shear-blade are returned to their starting position, the 90 detainer, however, continuing to hold the waste end of the thread clear of the subsequent stitching throughout a cycle of operations being then returned to starting position as hereinafter described. The second 95 cutting mechanism, in the form of a knife, is carried by a bellcrank-lever which is actuated through a slide-bar located beneath the bed-plate by the overthrow of the stop mechanism with which the machine is provided. The overthrow advances the knife against the limb of thread leading to the material and severs it close thereto and the usual return of the stop mechanism to its normal vertical position returns the knife 100 to starting position. When the knife is advanced to sever the thread the thread-end detainer is returned to starting position.

While the invention is applicable to machines of various types it is particularly adaptable to single chain-stitch machines for attaching articles to a body-fabric and is therefore shown herein embodied in a single-thread chain-stitch machine for sewing on buttons.

The invention further consists in certain details of construction which will appear in the following description of the device shown in the accompanying drawings, in which Figure 1 is a rear side elevation of the machine; Fig. 2 is a bottom plan view of the machine the parts being shown in starting position; Figs. 3, 4 and 5 are views of the T-lever and the throat-plate with the nipper, movable shear-blade, detainer and knife shown in the relative positions they occupy during their first, second and return stages of movement; Figs. 6 and 7 are perspective views of the detainer and the bell-crank-lever supporting the nipper and movable shear-blade; Fig. 8 is a perspective view of a pin-block; Fig. 9 shows the mechanism with the thread as it appears at the completion of the second stage of movement after it has been nipped against the throat-plate; Fig. 10 is a perspective view of the throat-plate showing the nipper and movable shear-blade in the position mentioned in Fig. 9; and Fig. 11 is a perspective view of the knife for cutting the thread from the supply.

The invention is shown applied to a chain-stitch machine having a needle 1 and operating under thread mechanism consisting of a non-thread carrying looper 2 and a needle-guard 3. The needle-thread passes from the supply through a constant tension device 4 to a clamp 5 which grips the thread when the needle-bar eye 6, constituting a take-up immediately adjacent the clamp, acts to set the stitch. The clamp 5 is intermittently actuated by a cam 7 on the needle-bar operating shaft 8 through a plunger-pin 9 in a manner well understood in the art.

The construction and operation of the looper 2 and loop-holding spur 10 are fully set forth in prior Patents Nos. 1,147,386 and 1,153,429, issued July 20, 1915 and September 14, 1915, respectively and reference may be had thereto for a full understanding of the same as specifically they form no part of the present invention and therefore require no detailed description.

A work-clamping mechanism 11 to which suitable jogging movements are imparted from a controller-cam 12, may be employed to hold an article such as a button. While any suitable adjusting mechanism for eliminating one of the component movements of the work-clamping mechanism and thereby changing from a four-hole to a two-hole button may be used, such being old expedients in the art, that shown in the drawings

at 13 is preferred and the construction thereof is fully described in my pending application Serial No. 100,804, filed May 31, 1916.

The elements acting upon the beginning end of the needle-thread at the commencement of a cycle of operations comprise a nipper 19, a movable shear-blade 20 and a detainer 40, all of which are constructed preferably of spring steel, are located below the throat-plate of the machine, and are actuated solely from projections on the periphery of the controller-cam excepting the return movement of the detainer to starting position which return movement is governed by the overthrow of a suitable stopping mechanism.

As shown in Fig. 10, there is pivoted on a stud 15 depending from within a shallow recess 16' in the throat-plate 16 and bored at 15' to receive a pivot pin 142 to be described later, a bellcrank 14 provided with a seat 17 in which are secured by a screw 18 the nipper 19 and the movable shear-blade 20 in superimposed relation. The nipper is arranged next to the throat-plate against which it grips the thread, while the movable shear-blade lies below the nipper with its cutting edge 21 slightly to the rear of a notch 22 in the nipper. A fixed ledger-blade 23 is adjustably secured to the throat-plate by means of a screw 24 and slot 25 and extends in the direction in which the nipper and movable blade are moved. This fixed ledger-blade is provided with a shearing edge 26 (Fig. 9) for coöperation with the cutting edge of the movable blade and it is also provided with an extension 27 which underlies both the nipper and the movable blade, being adapted to augment the spring pressure of the nipper and movable blade upward against the lower face of the throat-plate. A pin or friction roll 28, see Fig. 3, carried by one end of the bellcrank 14 is engaged by the forked end 30 of an arm 31 clamped by screw 32 to a slide-rod 33 arranged below the bed-plate of the machine.

The opposite end of the slide-rod is pinned at 34, see Fig. 1, to the vertical leg 35' of a lever 35 which rocks in a vertical plane about a fulcrum-screw 36 in a bracket 37 secured on the upper face of the bed-plate in juxtaposition to the periphery of the controller-cam 12. The lever 35 is T-shaped, as clearly shown in Fig. 1, and its fulcrum lies substantially at the junction of the vertical leg with the two offset horizontal arms 35^L and 35^R, which are inclined upwardly from the fulcrum of the lever. Fixed to the vertical leg 35' of the T-lever below the cloth-plate is a pin 135 adapted to engage the convex surface of a bow S' in a flat spring S adjustably secured to the cloth-plate in any suitable manner as indicated at S''. By this means the slide-rod 33 is held against movement excepting when positively 130

actuated by cams operating upon the arms 35^L and 35^R of the T-lever. These cams or projections indicated at A and B and arranged in pairs on the periphery of the controller-cam are adapted to rock the arms of the T-lever and swing the vertical leg thereof back and forth thereby reciprocating the slide-rod and actuating the nipper and movable shear-blade. It will be noticed—Figs. 3, 4 and 5—that a cam A is formed with an incline A' which merges into a concentric dwell portion A² at the end of which is a shoulder A³, while cam B has only one beveled or inclined face B'. The former moves the vertical leg of the T-lever to advance the nipper and movable blade in two stages while the latter moves the leg back to return them in a single stage movement to starting position. The cams A and B are adjustably secured to the controller-cam 12 by any suitable means such as the old and common slot and screw indicated at 38.

As shown in Figs. 2 and 6 a detainer 40 is clamped by a screw 41 to the short arm 42^s of an L-shaped lever 42 which is pivoted by a pin 142 intermediate the ends of its long arm 42^L coaxially with the bellcrank 14 carrying the nipper and movable blade. At the free end of the long arm 42^L a pin 42' is mounted to frictionally rub against the crook 43 formed in a flat spring 44 adjustably secured in any suitable manner to the frame of the machine, preferably, as shown, by the clip angle 45, slot and screw 46. As shown most clearly in Figs. 3-5 the detainer is moved in one direction, by a depending lug 14^L carried by the bellcrank 14 and engaging the long arm 42^L of the L-shaped lever 42, when the bellcrank is actuated to advance the nipper and movable shear-blade at the beginning of a cycle of operations. It is moved in the opposite direction, from the position shown in Fig. 5 to that shown in Fig. 2, by a bulge or enlargement 47 adjacent the bifurcated end 48 of a slide-bar 49 when the latter is reciprocated by the overthrow of a stop mechanism at the end of a cycle of operations, the said bulge or enlargement swiping a second pin 42'' fixed to the long arm of the L-shaped lever 42 carrying the detainer.

A single element acts on the finishing end of the needle-thread at the close of a cycle of operations. This element, a knife, severs the thread from the supply. The knife-blade 50, Fig. 11, is L-shaped and its cutting edge 50' is formed on a depending flange 50'' at its free end while its opposite end is suitably secured to a bellcrank-lever 51 pivoted on a pin 52'—Fig. 8—extending upwardly from block 52 which is fixedly secured to the throat-plate by means of a clamp-screw 52'', passed through the hole 53 therein, said pin being steadied by fitting it to a hole 54 also in the throat-plate Fig.

10. A pin 55, carried by the end of the bellcrank-lever 51 opposite to that to which the knife is secured, is embraced by the bifurcation 48 in the bent end of the slide-bar 49 which is slidably supported in suitable guideways 56 on the bottom of the bed-plate of the machine. This slide-bar is reciprocated by the overthrow of a stop mechanism.

The stop mechanism with which the machine is provided is arranged at the rear end of the machine. Such devices are old and well known, that shown being similar in its essentials to the construction shown in patent to Barron, No. 1,093,241, of April 14, 1914. As is well known, when one of several tripping points, not shown, engages a latch-lever 61, Fig. 1, during the last descent of the needle, a vibratory lever 62 pivoted at 63 is released by said latch-lever and allowed to move under the action of a flat spring 64 in a direction to carry its upper end, in which is contained a spring-pressed plunger 65, into engagement with a stop-cam 66 on the needle-bar operating shaft 8. The vibratory lever 62 is confined yieldingly against one of the spaced flanges 67 of the bracket 68 by means of a transverse plunger-rod 69 pocketed in the socket bearing boss 70 containing a buffer-spring, not shown. When the plunger 65 is engaged with the stop-cam 66 to lock the machine against further rotation the momentum of the moving parts is taken up and the jar reduced by the transverse plunger-rod 69 and buffer-spring which permit an overthrow of the stopping mechanism. This overthrow, as before mentioned, imparts a horizontal reciprocation to the slide-bar 49, through the bellcrank 49' pivoted at 49'' below the bed-plate, and thereby actuates the knife to cut the thread from the supply at the end of a cycle of operations and simultaneously returns the detainer to its initial starting position. The knife of course is returned to its initial position by the action of the buffer-spring in righting the vibratory lever 62.

From the foregoing description of the device the operation will be obvious. During the first reciprocation of the needle, the thread end is pulled through to the under side of the work-plate by the rotating looper. As the needle completes its first upward reciprocation the horizontal arm 35^L of the T-lever engages the incline A' of a cam A and imparts the first stage of movement to the nipper and movable shear-blade, the detainer 40 being compelled to move therewith by the lug 14^L carried by the bellcrank. The parts then are in the positions shown in Fig. 3.

The hooked end of the detainer defines a recess 40' which is slightly larger than that in the nipper but is in substantial registration therewith. As these members partake of their first stage of movement the hook of

the detainer deflects the beginning end of the thread to one side of the path of the needle and this deflection together with a diagonal jogging movement of the work-holding mechanism insures the loose enclosure or confinement of the thread on all sides by the edge of the needle-hole 16" in the throat-plate and by the recess 22 in the nipper preliminary to a gripping operation 5 which is thereby rendered certain of accomplishment. The first stage of movement given the nipper, movable blade and detainer is completed shortly after the needle starts down on its second descent. The 10 needle completes its second descent and rises and the thread below the throat-plate is pulled up by the action of the take-up and intermittent thread-clamp 5 so as to leave an end about $\frac{3}{8}$ of an inch long. When the 15 needle is about $\frac{1}{4}$ of an inch from the end of its second up-stroke, the shoulder A³ of a cam A engages the horizontal arm 35^L of the T-lever and imparts the second stage of movement to the bell crank 14 thereby causing 20 the nipper 19 to grip the thread against the throat-plate and, immediately thereafter or substantially simultaneously, the movable shear-blade 20 and detainer 40 cooperate with the fixed ledger-blade to cut and hold 25 the surplus length of the thread end. The parts at this time are in the relative position shown in Fig. 4. When the thread is nipped or just before that time the intermittent clamp 5 is opened. After sufficient stitches 30 have been formed to anchor the thread, and there is no further reason for holding the end thereof, the nipper and movable blade are returned to starting position by the incline B' of cam B which is engaged with 35 the other arm 35^R to rock the T-lever in the opposite direction thereby returning the slide-rod 33 connected with the bellcrank 14 to its normal or starting position. In the present instance the return of the nipper 40 and the movable shear-blade to starting position occurs during the fourth upward movement of the needle. The detainer 40, it is to be noticed, is not moved back with the nipper and blade as clearly appears in 45 the relative position of the parts shown in Fig. 5. It is returned to starting position at the end of a cycle of operations when the pin 42" carried by the detainer supporting lever is swiped by the enlarged bifurcated 50 end 48 of the slide-bar 49 and this swiping occurs when the slide-bar is actuated by the overthrow of the stop mechanism. Simultaneously with the return of the detainer the slide-bar 49, connected to the knife 50 by 55 the pin 55 carried by the bellcrank-lever 51, also engages the knife with the work limb of the needle-loop on the rotating looper which it severs close up to the material. 60

The above description relates to the construction in its preferred form but certain 65

features thereof are obviously capable of variation without departure from my present conception of the broad underlying invention. It will be obvious that the detainer for instance could be dispensed with entirely 70 for certain classes of work in which it would be immaterial if the surplus end of thread became entangled in the stitches and marred the appearance of the product. In short it is to be distinctly understood that I do not 75 wish my invention to be limited excepting as indicated by the definition of the invention in the claims.

Having thus set forth the nature of the invention, what I claim herein is:—

1. In a sewing machine making a predetermined number of stitches at an operation, a throat-plate, means for nipping the beginning end of a thread against said throat-plate, means for cutting said end comprising a ledger-blade carried by the throat-plate, a coacting blade carried by the nipping means, and an independently operated cutter for severing said thread at the end of the stitching operation. 85

2. In a sewing machine, automatic means for nipping a thread at the beginning of a stitching operation, separate cutting means carried by the thread-nipping means, and independently operated automatic means for cutting the thread at the end of the stitching operation. 95

3. In a sewing machine making a predetermined number of stitches in a prescribed path, in combination, means for nipping and cutting the thread during the first part of the operation of the machine and for detaining the cut-off portion, means for cutting the thread at the end of the operation of the machine, and means for pulling up the thread 100 before it is nipped to prevent waste. 105

4. In a sewing machine, in combination, means operating upon the beginning end of the thread to deflect, nip and cut it, and to detain the cut-off portion and additional 110 cutting means operating to sever the thread from the supply after a stitching operation has been completed.

5. In a sewing machine, means for successively deflecting, nipping and severing the 115 thread at the beginning of a sewing operation and for detaining the free end of the thread, means for releasing said free end at the end of a predetermined interval, and means for severing the thread at the end of 120 the sewing operation.

6. In a sewing machine, means for successively deflecting, nipping and severing the thread at the beginning of a sewing operation and for detaining the free end of the 125 thread, and means for releasing said free end and again severing the thread at the end of a predetermined interval.

7. In a sewing machine, thread-deflecting, nipping, cutting and detaining means, a 130

common actuating means therefor, means for returning said nipping and cutting means to inoperative position, a second thread-cutting means, and a common means for releasing 5 the detaining means and actuating said second cutting means.

8. In a sewing machine, in combination, means for deflecting the beginning end of the thread, means for subsequently nipping 10 said end, means for cutting off said end, said means for deflecting the thread operating to detain the end of the thread after it has been cut off to keep it clear of subsequently formed stitches.

15 9. In a sewing machine, means for nipping and cutting the beginning end of the needle-thread, in combination with a detainer acting upon the beginning end of the thread to deflect it before and detain it after 20 it has been cut off, and means for severing the finishing end of the thread from the supply.

10. In a sewing machine having a throat-plate, a nipper for nipping the needle-thread 25 end against the throat-plate at the beginning of a sewing operation, in combination with means for controlling the needle-thread mounted above the throat-plate and comprising a take-up, a tension, and a clamp ar- 30 ranged to grip the thread on the supply side of but immediately adjacent the take-up whereby stretching of the needle-thread is materially diminished and a tight stitch formed.

35 11. In a sewing machine having a throat-plate, a nipper mounted for movement below and nipping the thread against the throat-plate, a blade movable with the nipper and a ledger-blade coöperating with the movable 40 blade and having a projecting finger yield- ingly pressing the nipper and blade against the throat-plate whereby the needle-thread end may be held and cut immediately adja- cent the stitching point.

45 12. In a sewing machine, in combination, stitch-forming mechanism including a re- ciprocating needle and a coöperating non- thread carrying looper and work-clamping mechanism having suitable jogging move- 50 ments, of a free thread-end detainer, a nipper, and cutting mechanism all located below the throat-plate and operating upon the begin- ning end of the needle-thread during the formation of the first few stitches.

55 13. A thread-cutting mechanism for sewing machines comprising a throat-plate, a thread-nipper coacting therewith, coacting cutter-blades carried by the throat-plate and nipper, and a thread-detainer coacting with 60 one of said blades.

14. A thread-cutting mechanism for sewing machines comprising a throat-plate, and a simultaneous movable nipper, cutter and severed thread-end detainer carried in su- 65 perposed relation by said throat-plate.

15. A thread-cutting mechanism for sewing machines comprising a thread-nipper, a cutter and a severed thread-end detainer, means for moving said parts forwardly, means for retracting said nipper and cutter 70 after a predetermined interval, and means for retracting said detainer after a further interval.

16. In a sewing machine having a recessed throat-plate, movable nipping and shearing 75 members mounted in said recess for gripping and severing the beginning end of the needle-thread, said nipping member being located between the shearing member and said throat-plate, and fixed relatively to the 80 former.

17. In a sewing machine having a throat-plate, means for nipping the beginning end of the needle-thread and independent means for shearing said end of the thread, said 85 shearing means being provided with a tongue for yieldingly pressing the nipper against the throat-plate with which the machine is provided.

18. In a sewing machine having a throat-plate in combination, a spring nipper bearing against the throat-plate, a movable blade movable therewith, a fixed blade co-operating with the movable blade to shear 95 the thread, said fixed blade having a spring tongue underlying said nipper and said movable blade.

19. In a sewing machine, means for gripping the beginning end of a thread at spaced 100 points, means for severing said thread between said points, and means for successively releasing said gripping means.

20. In a sewing machine, means for gripping the beginning end of the needle-thread at two spaced points and means for severing 105 the thread therebetween.

21. In a sewing machine, means for gripping the beginning end of the thread at spaced points consisting of a nipper and a detainer, and a thread-guiding notch on one 110 of said parts.

22. In a sewing machine, means for gripping the beginning end of the thread at spaced points consisting of a nipper and a detainer, and means for severing the thread 115 between the nipper and detainer.

23. In a sewing machine, means for gripping the beginning end of the needle-thread at spaced points at substantially the same time, and means for successively re- 120 leasing said gripping means.

24. In a sewing machine, means for gripping the beginning end of the needle-thread at two spaced points at substantially the same time, and means for severing thread 125 between said points.

25. In a sewing machine, a throat-plate, and means located on one side thereof for substantially simultaneously gripping the beginning end of the needle-thread at spaced 130

- points consisting of a nipper and a detainer.
26. In a sewing machine, means for substantially simultaneously gripping the beginning end of the needle-thread at two spaced points consisting of a nipper and detainer, and means for severing the thread between said points.
27. In a sewing machine, means for gripping the beginning end of the needle-thread at spaced points, means for severing the thread therebetween, and means for severing the thread from the supply.
28. In a sewing machine, means for simultaneously gripping the beginning end of the needle-thread at spaced points, means for severing the thread therebetween, and means for severing the thread from the supply.
29. In a sewing machine, means for gripping the beginning end of the needle-thread at spaced points, means for shearing the thread between said points, and means for severing the thread from the supply after the stitching operation has been completed.
30. In a sewing machine, means for simultaneously gripping the beginning end of the needle-thread at spaced points, means for shearing the thread between said points, and means for severing the thread from the supply after the stitching operation has been completed.
31. In a single-thread chain-stitch machine having a needle and coöperative under-thread handling mechanism, means for intermittently clamping the needle-thread, means for taking up the needle-thread arranged to operate upon the thread between the needle and clamp, in combination with means located below the throat-plate for nipping the needle-thread during the second reciprocation of the needle and after the needle-thread end has been pulled up close to the under side of the throat-plate.
32. In a button sewing machine having a throat-plate, a reciprocating needle and coöperating under-thread handling mechanism, a work-clamp, in combination, a nipper for gripping the needle-thread against the throat-plate and a cutting mechanism carried by the nipper for severing the beginning end of the needle-thread close to the under side of the work, a main-shaft, and common means driven therefrom for actuating said nipper and said work-clamp.
33. In a button sewing machine having a throat-plate, a reciprocating needle and coöperating under-thread handling mechanism, a work-clamp, in combination, a nipper for gripping the needle-thread against the throat-plate and a cutting mechanism in superposed relation to said nipper for severing the beginning end of the needle-thread close to the under side of the work, a main-shaft, and a common means driven by said main-shaft for actuating the work-clamp, the nipper and the cutting mechanism.
34. In a sewing machine having a needle and coöperating under-thread handling mechanism, a throat-plate, and a main driving shaft, the combination of a work-clamp, a nipper, a cutting mechanism in superposed relation to said nipper for severing the beginning end of the thread, common means driven by said main-shaft for actuating the work-clamp, the nipper and the cutting mechanism, a stop mechanism, and a knife actuated thereby to sever the thread from the supply.
35. In a sewing machine having a needle and coöperating under-thread handling mechanism, a throat-plate, and a main driving shaft, the combination of a work-clamp, a nipper, a cutting mechanism for severing the beginning end of the thread, common means driven by said main-shaft for actuating the work-clamp, the nipper and the cutting mechanism, a stop mechanism, a cutter actuated thereby to sever the thread from the supply, and a detainer movable forward with the nipper to grip the thread and movable backward to starting position by said stopping mechanism.
36. In a button sewing machine having a needle, coöperating under thread mechanism and a throat-plate, the combination of a nipper, a movable shear-blade and a detainer arranged so that their thread-engaging portions are movable in a plane substantially parallel with the throat-plate, and a fixed ledger-blade with a shearing edge in a plane between said movable shear-blade and said detainer.
37. In a button sewing machine having a needle and coöperating under-thread handling mechanism, a throat-plate, a work-clamp, and a controller-cam for imparting suitable movements thereto, the combination of a nipper and a blade carried thereby located adjacent the throat-plate, said controller-cam being provided with suitable cam-faces for advancing said nipper and blade at the beginning of a sewing operation whereby the beginning end of the thread may be gripped and severed during the formation of the first few stitches.
38. In a sewing machine, in combination, a nipper and a shearing mechanism for gripping and severing the beginning end of the needle-thread, common means for actuating said nipper and shearing mechanism, and a detainer for gripping the free end of thread beyond the point where it is severed, said detainer being moved by said nipper to grip the thread end, and means for moving said detainer backward to starting position.
39. In a sewing machine, in combination,

a nipper and a shearing mechanism for gripping and severing the beginning end of the needle-thread, common means for actuating said nipper and shearing mechanism, and a 5 detainer for gripping the free end of thread beyond the point where it is severed, said detainer being moved by said nipper to grip the thread end, and independent means for moving said detainer backward to starting 10 position.

40. In a sewing machine having a reciprocating needle and coöperating lower-thread handling mechanism, means for nipping and severing the needle-thread, and 15 means for advancing said nipping and severing means in two stages at the beginning of a sewing operation to thereby during the first stage of advance deflect the free end of thread to one side of the needle-path and 20 control it during the second reciprocation of the needle and during the second stage of advance to grip and sever the thread.

41. In a sewing machine having a needle and coöperating lower-thread handling 25 mechanism, means in fixed relation to each other for nipping and severing the needle-thread, and means for advancing said nipping and severing means in two stages at the beginning of a sewing operation whereby 30 during the first-stage of advance the free end of thread is deflected to one side of the needle-path and during the second stage of advance it is gripped and severed, the two stages of advance occurring during the 35 first and second reciprocations of the needle respectively.

42. In a sewing machine, a needle and co-operating under-thread handling mechanism, a work-clamp, a controller-cam for 40 imparting suitable jogging movements to said work-clamp, in combination with a nipper and a shearing device having a movable blade both operating upon the beginning end of thread during the formation of 45 the first few stitches, said nipper and said movable blade being actuated by said controller-cam, and connections between said controller-cam and said nipper and movable blade including a plural-armed lever for effecting a two-stage advance and a single-stage return of the nipper and blade.

43. In a sewing machine, a needle and co-operating under-thread handling mechanism, a work-clamp, a controller-cam for 55 imparting suitable jogging movements to said work-clamp, projections on said cam, in combination with a nipper and a shearing mechanism having a movable blade both operating upon the beginning end of thread 60 during the formation of the first few stitches, said nipper and said movable blade being actuated by said controller-cam, and connections between said controller-cam and said nipper and movable blade including a plural-armed lever coöperating with said

projections on the cam for effecting a two-stage advance and a single-stage return of the nipper and blade.

44. In a sewing machine, a needle and co-operating under-thread handling mechanism, a work-clamp, a controller-cam for imparting suitable jogging movements to said work-clamp, in combination with a nipper and a shearing mechanism having a movable blade both operating upon the beginning end of thread during the formation of the first few stitches, said nipper and said movable blade being actuated by said controller-cam, and connections between said controller-cam and said nipper and movable 70 blade including a plural-armed lever for effecting a two-stage advance and a single-stage return of the nipper and blade, a stop mechanism and a knife actuated thereby to sever the thread from the supply. 75

45. In a sewing machine, a needle and co-operating under-thread handling mechanism, a work-clamp, a controller-cam for imparting suitable jogging movements to said work-clamp, in combination with a nipper and a shearing mechanism having a movable blade both operating upon the beginning end of thread during the formation of the first few stitches, said nipper and said movable blade being actuated by said controller-cam, and connections between said controller-cam and said nipper and movable blade including a plural-armed lever for effecting a two-stage advance and a single-stage return of the nipper and blade, a 80 stop mechanism and a knife actuated thereby to sever the thread from the supply. 85

46. In a single-thread chain-stitch machine for sewing on buttons having a needle and coöperating under-thread handling mechanism, a work-clamp, a controller-cam for imparting suitable jogging movements to said work-clamp and having beveled projections, in combination with a nipper, a 110

shearing mechanism including a movable blade, a thread-detainer, and a knife, connections between said controller-cam and said nipper and movable blade, including a plural-armed lever, a separable connection 115 between said nipper and said detainer, a stop mechanism, and a knife actuated thereby to sever the thread from the supply, said knife in its advance to sever the thread being adapted to return said detainer to 120 starting position.

In testimony whereof I have signed my name to this specification.

ALBERT F. FIFIeld.
